United States Patent Office

Des. 193,983
Patented Nov. 6, 1962

193,983

CONCRETE TILE

Frank A. Gory, Miami, Fla., assignor to Intercoastal Inc.,
Miami, Fla., a corporation of Florida

Filed June 29, 1962, Ser. No. 70,728

Term of patent 14 years

(Cl. D18—2)

The FIGURE is a perspective view of a concrete tile showing my new design.

The sides not shown are plain.

I claim:

The ornamental design of a concrete tile, as shown and described.

References Cited in the file of this patent

UNITED STATES PATENTS

D. 57,337 Heimerdinger ----- Mar. 15, 1921
2,319,857 Gray ----- May 25, 1943

OTHER REFERENCES

Western Architect and Engineer, September 1960, page
14, harlequin screen-wall illustration at top of page.